(57) **CLAIM**

The ornamental design for an independent rear suspension sub-frame support brace, as shown and described.

DESCRIPTION

FIG. 1 is a bottom right isometric view illustrating the independent rear suspension sub-frame support brace of the present invention;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.
